UNITED STATES PATENT OFFICE.

CHARLES DAVIS WELDON, OF MICA, WASHINGTON.

KNAPSACK.

SPECIFICATION forming part of Letters Patent No. 417,301, dated December 17, 1889.

Application filed April 22, 1889. Serial No. 308,124. (No model.)

To all whom it may concern:

Be it known that I, CHARLES D. WELDON, of Mica, in the county of Spokane and Territory of Washington, have invented a new 5 and Improved Knapsack, of which the following is a full, clear, and exact description.

The object of the invention is to provide a new and improved knapsack which is simple and durable in construction and adapted 10 to carry part of the wearer's load in front of the body in a pocket over each breast, thus distributing the load more uniformly on the shoulders and enabling the wearer to carry the load with more ease and comfort.

15 The invention consists of certain parts and details and combinations of the same, as will be hereinafter described, and then pointed out in the claims.

Reference is to be had to the accompanying 20 drawings, forming a part of this specification, in which similar letters of reference indicate corresponding parts in all the figures.

25 Figure 1 is a front perspective view of the improvement. Fig. 2 is a reduced rear perspective view of the same, and Fig. 3 is a rear perspective view of the improvement with several parts in open position.

The improved knapsack A is provided 30 with the usual bag or sack B, in which articles can be stored in the usual manner. On the sides of the bag B are arranged flaps C and C', adapted to fold over the rear of the bag to hold a blanket or other article located on the back part of the bag B in place. The 35 flaps C and C' are locked in place on the back of the bag B by straps D D, buckled into buckles D', said straps being secured on the flap C, while the buckles D' are held on the flap C'.

40 The top opening of the bag B is closed by the usual cover E, adapted to fold over the side flaps C and C' when the latter are in a closed position, as previously described. On the cover-flap E are secured the straps F, 45 adapted to buckle into the buckles F', secured to the bottom of the bag B. On the top of the cover-flap E are secured the straps G, adapted to receive the overcoat of the wearer of the knapsack, as plainly shown in 50 Fig. 2. On top of the cover-flap E are also secured buckles H H', in which buckle shoul-

der-straps I I', provided near their lower ends at their outer sides with straps J, buckling into the buckles J', fastened to the front of the bag B. The shoulder-straps I and I' are 55 preferably widened near their lower ends, so as to fully cover the breast of the wearer. The shoulder-straps I and I' can be connected with each other by straps K K² and buckles K' and K³, secured, respectively, to 60 the shoulder-straps I and I'. The buckles H H' are wide and short and rest directly upon the top of the cover-flap E, so that they do not chafe the shoulders nor scratch the gun when carried on the shoulder. 65

On the front of the shoulder-straps I and I' are secured the pockets L and L', having the cover-flaps N and N', each provided with a strap O, adapted to be buckled into a buckle O', secured to the lower end of the pocket L 70 or L', respectively. The pockets L L' are made narrow but long, and wide enough to pretty well cover each breast, and being made in this shape the pockets will hold a good deal without projecting far in front of 75 the body.

The knapsack is used as follows: When the device is in the open position, (shown in Fig. 3,) various articles can be stored in the bag B, and when the latter is filled the blanket is 80 placed on the outside of the back of the bag B, after which the flaps C and C' are folded over the blanket and buckled together by the straps D and buckles D'. The cover-flap E is then moved down over the opening of the 85 bag B and over the side flaps C and C', and is fastened in front by the straps F being buckled to the buckles F'. The folded over-coat is then placed in the straps G, as shown in Fig. 2. The straps K and K² are un- 90 buckled from their buckles K' and K³, so that the wearer can conveniently put his arms through the shoulder-straps I and I', after which the straps K and K² are buckled across the breast of the wearer to the buckles K' and K³.

The pockets L and L' can be filled with various articles, so as to counterbalance to a great extent the load in the bag B. When the pockets L and L' are filled, the flaps N 100 and N', respectively, are closed by the straps O being buckled to the buckles O'. Thus it

will be seen that the load carried by the wearer is equally distributed on the shoulders, enabling the wearer to carry the entire load with ease and comfort.

5 Having thus fully described my invention, I claim as new and desire to secure by Letters Patent—

1. The combination, with the knapsack, of the straps II', buckled at their upper ends to 10 the top of the knapsack, buckled at their sides, as at J', to the knapsack at or near its ends, the pockets L L' on the straps I I', and straps and buckles connecting the straps I I', substantially as set forth.

2. The combination, with a knapsack, of the 15 side straps I, buckled to the top thereof at their upper ends and widened at their lower ends to cover the breast of the wearer, and provided with pockets L L', straps and buckles J J', connecting the sides of the 20 straps I I' with the knapsack, and straps and buckles connecting the adjacent edges of straps I I', substantially as set forth.

CHARLES DAVIS WELDON.
